United States Patent Office

Des. 181,667

Patented Dec. 10, 1957

181,667

TELEPHONE RECEIVER ATTACHMENT OR SIMILAR ARTICLE

Mary V. Oyler, Dallas, Tex.

Application December 26, 1956, Serial No. 44,328

Term of patent 3½ years

(Cl. D26—14)

Fig. 1 is a side elevational view of a telephone receiver attachment or similar article, showing my new design;

Fig. 2 is a bottom plan view; and

Fig. 3 is a front elevational view.

I claim:

The ornamental design for a telephone receiver attachment or similar article, as shown.
